Primary Examiner—Lisa Lichtenstein(74) *Attorney, Agent, or Firm*—Morrison & Foerster LLP(57) **CLAIM**

The ornamental design for a ceiling fan housing, as shown and described.

DESCRIPTION

FIG. 1 is a perspective view of a fan housing in accordance with the present invention, the ceiling fan illustrates an environment for said fan housing;

FIG. 2 is an enlarged side view of the fan housing in accordance with the present invention;

FIG. 3 is another enlarged side view of the fan housing in accordance with the present invention;

FIG. 4 is yet another enlarged side view of the fan housing in accordance with the present invention;

FIG. 5 is yet another enlarged side view of the fan housing in accordance with the present invention;

FIG. 6 is an enlarged top view of the fan housing in accordance with the present invention;

FIG. 7 is an enlarged bottom view of the fan housing in accordance with the present invention;

FIG. 8 is an enlarged perspective view of the fan housing in accordance with the present invention; and,

FIG. 9 is another enlarged perspective view of the fan housing in accordance with the present invention.

The broken line showing of the ceiling fan mounting canopy, light kit, ceiling fan blades, support rod and switch housing is included for the purpose of illustrating environmental structure and forms no part of the claimed design.
